COASTER TOY

Max Heldman, Birmingham, Ala.

Application January 3, 1933, Serial No. 649,944

7 Claims. (Cl. 208—182)

My invention relates to a coaster stick for use when coasting on roller skates and the like.

More particularly, my invention consists in a stick or staff having adjustably mounted thereon a small, light seat and having at or near its lower end a roller support which normally runs in contact with the ground but which has associated therewith a ground engaging drag brake element adapted to be applied merely by varying 10 the angle of inclination of the coaster stick to the ground.

More particularly, my invention contemplates mounting on the lower end of the coaster stick, in juxtaposition to the roller support, an annular 15 brake shoe which is so mounted that it can be turned about the stick thereby to present different faces for wear and which preferably is so disposed and of such shape that when the forward end of the stick is raised the shoe will be 20 brought into contact with the ground so as to serve as a drag braking means.

My invention contemplates, as its preferred arrangement, the use of a pair of rollers mounted 25 on a clamp frame adapted for attachment to the stick near the end brake shoe. As an alternative arrangement, a single caster roller can be mounted at the lower end of the stick and the brake element in the form of a ring will then be set 30 in advance of it. In either case, by changing the normal riding angle of the coaster stick its brake can be brought into engagement with the ground and thus applied.

My invention further comprises the novel details of construction and arrangements of parts 35 which, in their preferred embodiment only, are illustrated in the accompanying drawing which forms a part of this specification, and in which

Fig. 1 is a side view showing the coaster stick toy in its preferred form with its drag brake 40 unapplied;

Fig. 2 is an enlarged view of the lower end of the stick showing the brake applied;

Fig. 3 is a sectional view taken on the line III—III of Fig. 2;

Fig. 4 is an enlarged side view of the coaster stick seat;

Figs. 5 and 6 are sectional views on the lines V—V and VI—VI respectively of Fig. 4;

Fig. 7 is a view similar to Fig. 2 of a modified 50 form of my invention using a single end caster wheel and an adjustable brake ring.

Similar reference numerals refer to similar parts throughout the drawing.

In the embodiment of my invention illustrated 55 in Figs. 1 to 6, I show the toy as comprising a

coaster stick or rod 10, preferably a cylindrical wooden staff such as is used for tool handles, and near its lower end I apply a mounting bracket for the roller support which comprises a pair of wheels 11, preferably mounted on ball bearings on an axle or bearing bolt 12 having a bolt head 13 at one end and a nut 14 screwed on its other end and serving to hold the wheels assembled with an interposed spacer sleeve 15 and end washers 16. The bracket comprises a loop ring 17 which partly surrounds the stick with parallel legs that receive a clamp bolt 18 beyond which the bracket legs are bent outwardly at 19 and downwardly at 20 where they are provided with aligning apertures to receive the wheel axle bolt 12. When the nut is applied to the bolt 18 it will engage a lower bracket member 19 so that it will not be rotatable. The bolt head is rounded and slotted so that a screw driver can be applied to it to tighten the bolt 18 and clamp the frame rigidly to the 20 stick and to the sleeve 15 on the roller assembly. By removing the nut 14 on the wheel assembly bolt 12 the adjacent wheel 11 can be removed, giving convenient access for the screw driver to tighten the bolt 18.

Thus the roller element as above described is clamped to the stick near its lower end, leaving sufficient space beyond it on the stick to receive the collar 21 on the shoe 22.

The collar has a plurality of pairs of aligning 30 holes 23 so that an attaching bolt or rivet 24 can be passed through one of these pairs and through a hole bored through the stick thereby to mount the brake shoe on the lower end of the stick. By 35 removing the bolt 24 and turning the brake shoe as it wears new surfaces can be presented until the shoe is worn out. The brake shoe may be made of a metal casting or of any tough durable material suitable, by engagement with the pavement or ground, to give sufficient wear as a drag 40 brake element.

I adjustably mount on the stick a seat of small light construction comprising the seat portion proper 25 having its edges rounded and terminating at its forward end in a pair of curved 45 clamp arms 26 and 27 which surround the stick and have interlocking tongues which when interlocked form a slip ring surrounding the stick. The seat is braced by a clamp strap comprising a center loop 28 which partly surrounds the stick and terminates in upwardly extending divergent 50 legs 29 that have out-turned top flanges that are riveted or spot welded to the under side of the seat near its marginal side edges. A clamp nut 30 and bolt 55 is inserted through the portions 29

and tightened to rigidly clamp the seat in position on the stick.

It will be apparent that the seat can be adjusted along the stick to suit the height of the child and, having clamped the brake shoe and roller support on the stick the toy is ready for the use indicated in Fig. 1, which shows a child coasting freely on the coaster stick and skates. Fig. 2 shows the inclination of the stick relative to the ground raised sufficiently to bring the brake shoe into contact with the ground or pavement so that it will act as a drag brake.

The roller bracket can be adjusted along the stick to suit the height of the child so that the brake shoe will just clear the ground when the child is riding the toy in a position which is natural and comfortable for him or her.

In Fig. 7 I show a modified form in which a single roller 32 is mounted in any suitable manner in a bearing bracket 33 made fast in or to the lower end of the stick 10. A brake ring 34 surrounds the stick above the roller and is provided with an attaching pin or rivet 35 and a plurality of aligning holes 36. Any suitable means may be used for adjustably mounting the brake ring in place on the stick so as to permit it, as it is worn, to be turned about the stick and present new wear faces for service. In the case of the brake shoe in Fig. 2 the shoe can be immovably mounted on the stick and by loosening the clamp bolts for the seat and roller mounting the stick itself can be turned so as to present a new wear face for the brake shoe without changing its position on the stick. With the toy shown in Fig. 7 the child applies the drag brake by lowering the angle of inclination of the stick to the ground until this brake is brought into engagement therewith.

Obviously, a roller support similar to that shown in Fig. 2 could be used in place of the caster roller 32 but such would require the brake ring 34 to be made of larger diameter thereby increasing its weight and cost, both of which factors are undesirable.

Also a ring brake like 34 could be applied below the rollers 11, but I prefer the use of a brake shoe that is lighter and looks more like a somewhat heavy ferrule for the stick 10 which gives a more trim and finished appearance to the toy.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior

art or as are specifically set forth in the appended claims.

What I claim is:

1. A coaster stick having a roller mounted at its lower end with a drag brake element comprising a body having an unreduced end forming a thick wearing portion, the element being mounted adjacent to the roller in position to be brought into engagement with the ground by varying the angular relationship of the stick to the ground by a rider astride the stick. 5

2. A coaster stick comprising a staff, a seat mounted thereon, roller means mounted on the lower end of the stick, a brake shoe surrounding the staff near the roller means, and means to change the relative position of brake shoe on the staff to present different wear surfaces on the brake shoe for ground engagement. 10

3. A coaster stick comprising a staff, a seat mounted thereon, a roller bearing frame mounted on the lower end of the staff, and a cast iron brake shoe on the staff adjacent to the roller frame and comprising a body enlarged to provide a thick wearing portion projecting into juxtaposition to the ground when the stick is in coasting service. 20

4. A coaster stick comprising a staff, a seat adjustably mounted thereon, a roller bearing frame adjustably mounted on the lower end of the staff, and an interchangeable and adjustable metallic brake shoe on the staff adjacent to the roller frame and having an enlarged annular wear face projecting into juxtaposition to the ground when the stick is in coasting service. 30

5. A coaster stick comprising a staff, a roller bearing frame mounted on the lower end of the staff, a brake shoe on the shaft adjacent to the roller frame, and means to permit said brake shoe to be angularly adjusted about the staff to present new working faces to the ground. 40

6. A coaster stick comprising a staff, a roller mounted at the lower end of the staff, and a drag brake mounted on the staff above the roller in position to engage the ground when the staff is rocked downwardly in the direction of travel 45 below normal coasting position.

7. A coaster stick comprising a staff, a single pair of rollers and a bearing therefor fixedly mounted near the lower end of the staff, and a metallic drag brake mounted for adjustment about the end of the staff below the rollers and projecting downwardly in position to engage the ground when the staff is rocked upwardly above normal coasting position. 50

MAX HELDMAN.
